CLAIM

The ornamental design for a push-rod for retrieving tool, as shown and described.

DESCRIPTION

FIG. 1 is a perspective view of the push-rod for retrieving tool showing my new design;

FIG. 2 is an enlarged fragmentary perspective view of the upper hook-end thereof;

FIG. 3 is an enlarged fragmentary perspective view of the bottom T-shaped end thereof;

FIG. 4 is a top plan view thereof;

FIG. 5 is a bottom plan view thereof;

FIG. 6 is a side elevational view thereof; the opposite side being a mirror image; and

FIG. 7 is an enlarged fragmentary elevational view of the central section as shown in FIG. 6.

FIG. 1
